UNITED STATES PATENT OFFICE.

RUDOLPH KRENZ, OF MIDDLETOWN, CONNECTICUT, ASSIGNOR TO THE RUSSELL MANUFACTURING COMPANY, OF MIDDLETOWN, CONNECTICUT, A CORPORATION.

SHUTTLE MOTION AND CARRIER.

1,281,536.

Specification of Letters Patent. Patented June 26, 1917.

Application filed August 21, 1916. Serial No. 116,070.

To all whom it may concern:

Be it known that I, RUDOLPH KRENZ, a citizen of the United States, residing at Middletown, in the county of Middlesex and 5 State of Connecticut, have invented certain new and useful Improvements in Shuttle Motions and Carriers, of which the following is a specification.

My invention relates to improvements in 10 shuttle motions and carriers as applied to looms adapted for weaving goods that are relatively narrow, and the object of my improvement is to provide means that can be incorporated in looms already in use, of the 15 class mentioned, involving a substitute for the rack and pinion method in common use, and that is simple and economical in construction and convenient and reliable in use.

In the accompanying drawing:

20 Figure 1 is a front elevation of part of a lathe of a loom equipped with my improved shuttle motion and carrier.

Fig. 2 is a plan view of the same.

25 Fig. 3 is a sectional view, on an enlarged scale, on the line *xx* of Fig. 1.

Fig. 4 is a bottom view of the cam.

30 Fig. 5 is a front elevation on a considerably reduced scale of the shuttle and connected parts.

The lathe shown in Fig. 1 comprises the usual block or timber 10 that supports the usual guide-ways for the shuttle 11, consisting of the lower guide 12 and the upper guide 13, arranged in pairs, and interrupted 35 by the weaving space 14, in which are located the shed and the reed when in use. The timber 10 is elongated and a plurality of sets of guide-ways are mounted thereon for the simultaneous operation of a corresponding plurality of shuttles 11, only one set however being shown in the drawing.

The individual guides 12 and 13 are short, and are secured to a pair of posts 15 by means of screws 16, the posts 15 extending 40 upwardly from the timber 10.

The opposed faces of the guides 12 and 13 have longitudinally extending ribs 17 that coöperate with corresponding grooves 18 on the lower and upper faces of the shuttle 11 50 and serve as the guides proper.

The shuttle 11 as usual is of appreciably greater length than the gap 14 caused by the interruption of the guide-ways to provide the weaving space, suitably to bridge the

said gap and to provide for properly guiding the shuttle 11, whereby during the travel of the shuttle 11 it will alternately be positioned at first entirely between one pair of guides 12 and 13, then in bridging the gap will be partially engaged with the two pairs 60 of guides, and finally will pass over entirely to the other, mating pair of guides 12 and 13 on the other side of the gap 13.

The parts described and the movements thereof are essentially ordinary.

The carrier means for effecting the movement of the shuttle described and the movement for imparting motion to the said carrier means are of special construction, as 70 will be described herewith.

The individual guides 13 that combine to form the upper member of the guide-way for the shuttle 11 are provided on the upper face with a longitudinally extending rib 19. Opposed to the said rib 19 and in spaced 75 relation thereto is a guide-rib 23 on the lower face of a longitudinally extending guide-strip 20 secured to the posts 15 by screws 21. Slidably engaged with the guide-way formed by the ribs 19 and 23 is a carriage or carrier 22 that supports the shuttle 80 engaging devices and to which motion is imparted by the movement referred to above.

The said movement comprises a shaft 24 mounted on one end of the timber 10 by means 85 of a standard 25. A sprocket wheel 26 mounted on the shaft 24, operated by a sprocket chain 27, imparts a rotary movement to the shaft 24. The connection between the shaft 24 and the carrier 22 comprises a crank arm 28 mounted on the said shaft 24 and a connecting rod 29 connecting the free end of the said crank arm 28 with one end of the said carrier 22.

As the shaft 24 is rotated a reciprocating 95 movement is imparted to the carrier 22.

In use I prefer to impart a partial rotation only to the shaft, first in one direction and then a return movement, with a dwell at the end of each movement, the movement 100 being effected by a pull first on the portion of the sprocket chain 27 on one side of the sprocket wheel 26 for movement in one direction and then on the portion on the other side for the return movement.

The shuttle engaging devices comprise a pair of swinging dogs pivotally mounted on the carrier 22 that engage by their lower,

free ends 31 with the coöperating grooves 32 in the upper face of the shuttle 11. The mounting for the dogs 30 comprises a bracket 33 secured to the carrier 22 by the screws 34. On the front portion of the bracket 33 is a channel 35 of appreciable length, vertically directed and having the bottom or rear wall 37 in alinement with the rear, end wall 36 of the groove 32. The side walls 38 of the channel 32 are spaced suitably to provide an operative fit for the dog 30. The pivotal pin 39 extends across the channel 35, adjacent the upper end thereof.

15 The dog 30 comprises a straight rod, pivotally mounted on the pivotal pin 39, the lower portion extending downwardly through the channel 35 and into the groove 32 under normal conditions, the upper portion extending an appreciable distance above the pivotal pin 39, a bearing roller 40 being mounted on the extreme upper end. The rear wall 37 of the channel 35 is cut away at the upper end to permit the upper end of the dog 30 to swing rearwardly as the dog 30 is swung on the pivot 39. The dog 30 is thus free to have the lower end 31 swing forwardly, so as to become disengaged from the groove 32, the rearward movement, however, of the said lower end being limited by the rear wall 37 of the channel 35.

35 The two dogs 30 that engage with the shuttle 11 are spaced laterally by a space appreciably greater than the width of the weaving space 14, and one of the dogs at least is always in engagement with the shuttle 11 when the shuttle is positioned in the said space 14, although each dog 30 while traveling across the weaving space 14 is disengaged from the shuttle 11.

40 The means for operating the dogs 30 so as to effect the engagement and disengagement thereof with the shuttle 11 consists of a cam 41 having a groove that is an operative fit for the bearing roller 40.

45 The cam 41 comprises a single casting, secured to the posts 15, having the said groove 42 on the lower side. The said groove 42 comprises end portions 43 positioned directly over the line of movement of the pivotal pin 39, suitable to position the dogs 30 vertically so as to be in position of engagement with the shuttle 11, a middle portion 44 over the weaving space 14, 50 suitable to tilt the dogs 30 to the position of disengagement from the shuttle 11, and intermediate portions connecting the end portions 43 with the middle portion 44.

I prefer to mount the cam 41 on a plate 60 45, as shown, the said plate 45 being mounted on the posts 15, and extending the full length of the structure, the portion bridging the weaving space 14 serving as one of the guides for the reed. A second plate 65 46, let into the posts 15, and spaced rear-

wardly from the front plate 45, serves as the rear guide for the reed.

The shuttle motion and carrier described are adapted to be applied to looms already in use, the changes being limited essentially 70 to providing the grooves or slots in the shuttle, the other parts needed being additional parts that are applied to the loom, rather than changes in the original structure.

Furthermore, the upper individual guides 75 13 for the shuttle 11 serve as the lower guide for the carrier.

By providing the channel for the dogs as described the dogs are held for an appreciable portion of their length while in engagement with the shuttle.

The end portions 43 of the cam groove serve to bring the dogs 30 to the vertical, engaging position, as shown in Fig. 3, and as the movement of the carriage brings the 85 dogs laterally to one side or the other of the cam 41 such vertical position is maintained by the rear edge of the roller engaging with the front face of the upper guide member 23 for the carriage, a portion of said guide member 23 being shown in end elevation in the said Fig. 3. That is to say, the cam with its groove serves to effect the necessary movements of the dogs in traveling across and for a short distance each side of the 95 weaving space, and on either side of the said cam no groove is necessary to hold the dogs in engaging position, the front face of one of the guide strips serving to effect the necessary guiding.

100 While I prefer to provide a roller for the dogs as shown, in some cases the roller may be dispensed with.

I claim as my invention:—

1. In combination in a lathe for a loom, a 105 guide way for the shuttle, interrupted by a weaving space, a shuttle positioned in the said guide-way having a transverse slot adjacent each end, on the upper side, a carrier slidably mounted above the said guide-way, a cam positioned above the said weaving space, having a cam groove, a pair of dogs pivotally mounted on the said carrier, the lower ends being adapted to engage with the said slots, and the upper ends having 110 rollers that are operative in the said cam groove.

2. In a lathe for a loom, a pivotally mounted dog for engaging with the shuttle, the said dog being in the form of a rod, having 120 pivotal supporting means intermediate the ends, one of the said ends being provided with guide means for tilting the said dog on the said pivotal supporting means, the other end serving to engage with a groove in the 125 said shuttle, the body portion of the said dog between the said pivotal supporting means and the said other end being of appreciable length, and a channel fitting and engaging with the said body portion for 130

steadying the said dog while the said other end is engaged with the shuttle.

3. In a loom comprising a pair of swinging dogs that serve as actuating devices for the shuttle comprising in combination a bracket and a dog pivotally connected to the said bracket, the said bracket having a vertical channel of appreciable length, and open at the front side, the said dog being in the form of a rod, fitting in the said channel and extending through the same, pivotally connected to the upper end of the said channel, the lower end of the said dog being adapted to engage with a groove in the shuttle, the upper end of the said dog being provided with a roller, and a member positioned above the said bracket, the said

member having a cam groove for coacting with the said roller.

4. In a loom, a carriage, guide strips 20 therefor, a pair of swinging dogs operatively mounted on the said carriage, the said dogs serving as actuating means for the shuttle, a cam having a groove for engaging with the said dogs serving to guide the said dogs 25 in their movement across the weaving space, and the face of one of the said guide strips serving as the guiding means for the said dogs to one side of the said cam.

RUDOLPH KRENZ.
